UNITED STATES PATENT OFFICE.

JAMES D. ROBERTSON, OF LA SALLE, ILLINOIS.

ELECTRIC RAILWAY.

SPECIFICATION forming part of Letters Patent No. 659,550, dated October 9, 1900.

Application filed January 31, 1900. Serial No. 3,453. (No model.)

To all whom it may concern:

Be it known that I, JAMES D. ROBERTSON, a citizen of the United States, and a resident of La Salle, in the county of La Salle and State 5 of Illinois, have invented a new and Improved Electric Railway, of which the following is a full, clear, and exact description.

This invention relates to improvements in electric railways, in which an electric supply conductor is arranged in a conduit or between the track-rails; and the object is to provide an electric railway that shall be comparatively cheap to construct and maintain in order and having in it a conductor for a heating medium to prevent an accumulation of snow or ice around the distributing rails or cables that may be arranged in a system, and, further, to so arrange the heat-conductor that it also may be used as a conductor to supply 20 electricity to a car-motor.

I will describe an electric railway embodying my invention and then point out the novel features in the appended claims.

Reference is to be had to the accompanying 25 drawings, forming a part of this specification, in which similar characters of reference indicate corresponding parts in all the figures.

Figure 1 is a perspective view of an electric railway embodying my invention. Fig. 2 is 30 a plan view thereof. Fig. 3 is a cross-section showing a slight modification. Fig. 4 is a diagrammatic view of the system. Fig. 5 is a side view showing the connections of the conducting-pipe sections, and Fig. 6 shows a 35 manner of connecting the heat-supply with the heat-conducting pipe when said pipe is also used as a conductor for electricity.

Referring to the drawings, 1 designates the ordinary track-rails, secured to the cross-ties 40 2 in the usual manner. Secured to the ties 2 at the inner side and adjacent to the rails 1 are string-pieces 3, consisting of suitable metal, and each string-piece has a flange portion to bear upon the ties and through which 45 fastening-bolts may pass or with which spikes may engage. At the upper portion of each string-piece is an inwardly-extended flange 4.

Arranged centrally between the track-rails are string-pieces 5, also consisting of metal 50 and having at the upper portion inwardly-extended flanges 6, the flanges of the two

stringers being placed apart to permit the entrance of a trolley or collecting device.

Supported on the string-pieces 3 and intermediate string-pieces 5 are bed-plates 7, consisting of metal of sufficient thickness to bear the weight of traffic that may be placed upon them. These plates engage with the flange portions 4 and 6, and they are further supported between the string-pieces by metal 55 posts 7^a, mounted on the cross-ties and supporting on their upper ends supporting-plates 8, which extend longitudinally of the track and engage against the under sides of the plates 7. The space between the outer string-pieces and intermediate string-pieces may be utilized as conduits for cables 9, designed to conduct electricity for any desired purpose—such as for running motors in factories, heating purposes, or the like—and these spaces 60 may also be utilized for wires 10, as shown in Fig. 3, for conducting telegraph or telephone messages. These wires 10 are shown as supported on insulators mounted on brackets extended inward from the outer string-pieces 3. 65 The space between the upwardly-extended portions of the string-pieces 5 is utilized as a conduit for a conductor or conductors for a heating medium and electricity. In Figs. 1 and 2 I have shown a pipe 11, which may be 70 made of any suitable metal, as extended through this conduit. This pipe is designed to convey a heating medium—such, for instance, as steam—which may be supplied from a power-house and also from any other points 75 or stations along the road. In Fig. 4 I have shown the pipe 11 as connected to a steam-boiler 12 by means of a pipe 13, having a flexible connection 14, with an elbow 15, (shown in Fig. 6,) which communicates with the pipe 80 11 at the under side. By thus connecting the pipe 13 with the pipe 11 a smooth continuous surface is left on the upper side, so that there will be no obstructions to the collector carried by a car running over the same, while 85 the pipe is used as a conductor for electricity. The supply-pipe 13 will be provided with a suitable valve 16, and the elbow 15 is shown as having a valve-controlled waste-pipe 17, which may lead to a sewer and through which 90 water of condensation collecting in the elbow 95 may discharge. The conducting-pipe 11 is 100

made in sections of suitable lengths, and to avoid obstructions on the top certain of the sections are connected by an exterior screw-thread 18, formed on the reduced portion of 5 one of the sections and engaging an interior screw-thread on the other section.

To provide for the contraction and expansion of the pipe and to prevent its buckling or movement out of position, at certain intervals I connect sections of the pipe by a 10 flexible joint 19. This flexible joint is connected to a downwardly-turned portion 20 of one pipe-section and to a downwardly-turned portion 21 of an adjacent section. This portion 21 has a horizontal extension 22, to which the joint 19 is directly connected, and with this part 22 a valve-controlled discharge-pipe 23 connects. This pipe 23 may lead to a 15 sewer, and it is designed to discharge water 20 of condensation that may collect. To provide a continuous passage between the pipe-sections at this portion, a transversely-curved bridge-piece 24 is rigidly connected to one of the pipe-sections and is adapted to slide on 25 the other section during the expansion or contraction of the pipe.

The pipe in Fig. 1 is shown as resting on rollers 25, consisting of insulating material, such as porcelain or the like. In Fig. 3, however, a heating-pipe 26 rests on blocks 27, of 30 insulating material, attached to the ties. This pipe 26 in this example of my improvement is for heating purposes only, and therefore I provide above the same a conducting-wire 28, 35 supported on rods 29, attached to the vertical portions of the string-pieces 5, but insulated therefrom. It will be noted that the vertical walls of the string-pieces 5 are provided with openings 30, through which heat may pass to 40 the spaces below the plates 7 for the purpose of preventing the formation of ice in the said spaces.

The operating-current, as shown in Fig. 4, is supplied to the conductor within the conduit from a generator 31 through a wire 32, and the return current after passing through 45 the motor of a car is taken through one of the rails and a wire 33 to the generator.

It will be noted that the plates 7 are inclined downward from the center and that the upper edges of the string-pieces 3 are substantially on a plane with the top of the rails 1. 50

The heating medium passing through the pipe will not only keep the spaces below the 55 plates warm, as before described, but will also heat the plates 7 in such manner as to keep them practically free from snow and ice, and from these plates the rails 1 will also be sufficiently heated to keep them free from snow 60 or ice. The top plates 7 may be of any desired length, and they may have their adjacent edges overlapped, if desired, to form water-tight joints. By making these plates in comparatively-short lengths it is obvious that 65 desired sections may be easily removed for the placing in or taking out of wires or ca-

bles, as desired, without disturbing other portions of the road.

It is also obvious that my invention may be readily applied to a railroad already laid, as 70 it is not necessary to dig trenches for conduits, as is generally the requirement in underground-trolley systems.

Having thus described my invention, I claim as new and desire to secure by Letters 75 Patent—

1. In an electric railway, bed-plates supported between the rails, supports for the inner sides of said plates, the vertical walls of said supports forming walls for a conduit, 80 and a conductor arranged in said conduit, substantially as specified.

2. In an electric railway, string-pieces arranged adjacent the inner sides of the rails, intermediate string-pieces spaced apart to 85 provide a slot between them, the said intermediate string-pieces having openings through their vertical walls, bed-plates removably attached to the string-pieces, and a heat-supply pipe arranged between the intermediate 90 string-pieces, substantially as specified.

3. In an electric railway, string-pieces arranged adjacent the inner sides of the railway-rails, intermediate string-pieces having a space between them, metal plates removably secured to the string-pieces, and supporting-posts for the plates between the 95 string-pieces, substantially as specified.

4. In an electric railway, string-pieces arranged along the inner sides of the railway-rails, intermediate string-pieces, a heat-conducting pipe arranged between the intermediate string-pieces, bed-plates removably secured to the outer string-pieces and intermediate string-pieces, supporting-plates engaging 100 with the under sides of the bed-plates, and posts upon which said supporting-plates rest, substantially as specified.

5. In an electric railway, bed-plates supported upon the cross-ties of the railway and 110 between the track-rails, forming the upper walls of a conduit in which electric wires or cables may be placed, string-pieces supporting the inner edges of said plates and having openings through their vertical walls, and a 115 pipe for conducting a heating medium arranged between said string-pieces, substantially as specified.

6. In an electric railway, a pipe serving as 120 a conductor for a heating medium and also as a conductor for electricity, the said pipe being formed in sections, adjacent ends of certain sections being extended downward, a flexible joint between said downwardly-extended portions, and a bridge-piece rigidly 125 connected to one section and having sliding connection with the other section, substantially as specified.

7. In an electric railway, a pipe serving to 130 conduct a heating medium and also serving to conduct electricity, the said pipe being made in sections, certain of said sections be-

ing turned downward and connected together by a flexible joint, a discharge-pipe connecting with one of said downward extensions, and a bridge-piece secured to one of the sections and adapted to slide on the other section, substantially as specified.

8. In an electric railway, a conduit arranged between the rails, a pipe arranged in said conduit, said pipe being made in sections, certain of the sections being connected by a flexible

joint, and rollers in the conduit on which said pipe rests, substantially as specified.

In testimony whereof I have signed my name to this specification in the presence of two subscribing witnesses.

JAMES D. ROBERTSON.
